UNITED STATES PATENT OFFICE.

HENRY T. BARTLETT, JOHN E. BARTLETT, AND JESSE T. ROBINSON, OF MONTGOMERY, ALABAMA.

DELIVERY-CABINET.

1,239,663.

Specification of Letters Patent. Patented Sept. 11, 1917.

Application filed August 19, 1916. Serial No. 115,805.

To all whom it may concern:

Be it known that we, HENRY T. BARTLETT, JOHN E. BARTLETT, and JESSE T. ROBINSON, citizens of the United States of America, residing at Montgomery, in the county of Montgomery and State of Alabama, have invented certain new and useful Improvements in Delivery-Cabinets, of which the following is a specification.

10 Our invention relates to a cabinet or container for holding a stack of bank checks, deposit slips, sheets of writing paper, or slips of material which will be delivered one at a time for use by the manipulation of a 15 feed mechanism, the object of the invention being to avoid by this *seriatim* delivery of the articles the loss and waste incident to the promiscuous use or removal of such articles by customers and others.

20 Our invention is more particularly intended as an apparatus for preventing the waste of counter-checks and deposit slips which at present are left exposed on the bank counters in large quantities, generally 25 in pads, and which are appropriated by the customers of the banks and others for use as scratch pads or for other purposes foreign to the business of the institution providing them. We have conceived that, if a simple 30 and inexpensive apparatus can be provided which is attractive in appearance and can be conveniently placed upon the counters and which must be operated each time a slip, check or the like is desired, a large 35 percentage of this waste will be obviated and to this end we have designed a cabinet adapted to receive and hold a stack of slips or blank checks. Adjustable mechanism is provided to hold the stack of slips in position before the delivery chute and the delivery mechanism is provided and adapted to be equally effective, regardless of the height 40 of the stack of slips, to deliver them *seriatim* in position to be grasped and drawn out by 45 the user.

Our invention comprises many novel details of construction, the nature and purposes of which will be understood by reference to the accompanying drawings which 50 are intended to illustrate only the preferred embodiment of our invention and in which:—

Figure 1 shows the complete apparatus in perspective with the top part of the cabinet shown in dotted lines.

Fig. 2 is a partial vertical sectional view illustrating the delivery end of the apparatus.

Fig. 3 is a plan view showing the movable post supports below the pedestal in dotted 60 lines.

Fig. 4 is a vertical sectional view on the line 4—4 of Fig. 3.

Figs. 5 and 6 are detail views in plan and elevation, respectively, of the adjustable 65 friction member for resisting the outward movement of the articles.

Similar reference numerals refer to similar parts throughout the drawings.

The apparatus, as illustrated, comprises 70 a suitable base or pedestal 10 preferably in the form of a box open below and supported by soft pads 11 to protect the counter or desk upon which the apparatus is placed. The base comprises a flat top or platform 12 75 which receives the stack of articles 13, such as checks, deposit slips and the like. Near the back end of the platform 12 and along its center line is a series of screw threaded holes 14 adapted to receive the lower threaded end 80 of a stop or post 15 and permitting the post to be adjusted lengthwise of the platform to accommodate varying lengths of stacked slips and hold their forward ends adjacent to an upwardly inclined delivery plate 16 85 leading to a feed slot 17 in the front end 18 of the top of the apparatus. This plate 16 is movable with the top and when in operating position extends from below the platform level to and beyond the slot 17, forming 90 the bottom of the latter.

The platform near its forward end is provided with a pair of guide posts 19 which project through arcuate slots 20 at each side and are riveted or made fast to the forward 95 ends of bars 21, which extend diagonally across under the platform and have their central lapping portions pivotally connected to the platform by a rivet or bearing stud 22. At their rear ends each bar 21 carries 100 an upright post 23 which projects up through a slot 24 on each side of the platform. The several slots are struck on arcs from the bearing 22 and elongated to permit the posts of each pair to be swung toward 105 and from each other and thus vary the spacing between them to accommodate different widths of checks, slips or like articles. The right hand post 23 at its upper end is reduced to form a vertical bearing 110

pin 25 upon which a rocker arm 26 is journaled and held in place by a top washer 27 riveted on the bearing pin. The rocker arm 26 is free to swing horizontally and at its 5 outer end carries a straight presser rod 28 which projects downwardly at a slight outward angle (see Fig. 5) through the adjacent platform slot 24. A sleeve 29 of rubber or like frictional material is fitted over 10 the presser rod 28 and a similar sleeve 30 is mounted on the left hand post 23. A coil spring 31 engages the presser rod 28 and is connected to the adjacent post 23 and tends to swing the rod about the post and 15 press it against the side edges of the stack of slips, it being noted that its angular disposition causes it to exert its friction pressure upon the upper slips only of the stack, and that this action is true regardless of 20 the height of the stack. Links 32 are connected to the rear ends of the bars 21 and are in turn connected to a slide pin 33 working in a longitudinal guide 34 in the under side of the platform. The bar 21, adjacent 25 to the right hand post 19, is formed with a lateral extension 35 in which is journaled a swivel block 36 having a threaded hole therethrough to receive the threaded end of an adjusting screw 37. This screw has 30 fast on its outer end a plunger 38 which works in a socket 39 formed in a boss 40 in the side of the pedestal. A coil spring 41 surrounds the screw bearing at one end against the boss and at its other end against 35 a collar 42. The spring urges the bars through their lazy-tong connections to press the several posts against the stack of slips and the plunger, by engaging the inner wall of the socket, serves to limit the inward 40 spring-pressed movement of the posts. By turning the screw the pairs of posts can be set nearer or farther apart without disturbing the action of the spring and stop thereon.

At the rear end of the platform is a 45 bracket 43 having forwardly extending end flanges through which passes a bearing pin 44. The metallic casing 45 forming the top of the cabinet is journaled at its rear end on the ends of the pins 44 and can be adapted 50 to be opened up to a vertical position so as to fully expose the platform. This top, at its forward end, carries the parts 16, 17 and 18 and also carries a latch 46 which is adapted to engage a latch pin 47 below the 55 platform, a spring 47^a pressing the latch toward its pin engaging position and a slot 48 in the platform being provided to permit the latch to project down therethrough and engage the pin. The outer end of the 60 latch projects through the guide plate 16 in convenient position to be pressed by the hand when in position to lift the top.

A curved operating lever 49 is mounted at one side of the apparatus and at its forward end carries a handle 50 which pro-

jects through a slotted guide 51 near the top of the apparatus, and at the other end the lever is pivotally connected to a bow lever 52, the side members of which are pivotally connected by pins 53 to the sides 70 of the top and at their upper ends are connected by a cross arm 54. A bar 55 is pivotally connected to the center of the cross arm 54 and extends forward of the machine, having its forward end pivotally connected 75 to a pin 56 on a rocker arm 57 mounted to rock on a bearing 58 on the side of the top. Coil springs 59 hold the rocker arms retracted and the handle at the rear end of the slot 51. At the center of the arm 80 55 is an enlargement carrying journal pins disposed in vertical alinement and having mounted thereon a pair of parallel bars 60, which bars at their forward ends are pivotally connected to a pusher plate 61 having 85 its main body portion twisted to lie in a transverse plane and covered with a rubber or friction pad 62. A coil spring 63 mounted on the bar 55 engages and depresses the bars 60, thus urging the pusher plate toward 90 the pad sheets. The top 45 of the apparatus has a glass cover 64 which exposes to view the stack of slips to be distributed.

The operation of the apparatus is as follows: Assuming that a stack of counter-checks are to be handled, the top 45 is raised, the left hand posts 19 and 23 are grasped and drawn together by which action all of the posts are spaced apart and the checks can be placed between the posts on the platform 12. The post 15 is adjusted to the proper hole to bring the forward ends of the checks near enough to the feed slot 17 to be projected therethrough by the pusher plate. By turning the screw 37 the relative 105 adjustment of the posts can be adapted to the size of the checks, the posts 19 serving preferably merely as guides while the presser rod 28 and the opposite post 23 between them frictionally engage the side edges of 110 the stack of checks sufficiently to resist their outward movement. The top 45 is now lowered and in doing so the pusher plate 62 engages the top check of the stack. As the handle 50 is drawn forward it rocks the 115 arms 52 and 57 forward, carrying with them the bar 55 and moving forward with the bar the parallel bars 60 and the pusher pad 62, which frictionally engages, and in moving from its full line to dotted line position, 120 Fig. 2, feeds forward a check in position to be grasped and drawn out by the operator. Upon releasing the handle the springs 59 return the pusher mechanism to retracted position, as shown in full lines Fig. 2. As 125 the stack is lowered the spring 31 swings the presser rod 28 about its supporting post 23 and causes the inclined surface of the former to press always with its greatest force on the upper sheets. In like manner the spring 63 130

and the weight of the pusher, cause the latter to follow down, as the stack diminishes, and to work as effectively to feed the first as the last article. Either the weight or the spring 5 may be relied upon.

The apparatus is especially designed for feeding checks, slips and the like *seriatim*, and obviously it may be modified in design and construction to handle tickets, envelopes, 10 writing paper, and like articles. It will also be understood that various modifications may be made in the apparatus which we have attempted to describe only in what we now regard as its preferred embodiment.

15 What we claim as new and desire to secure by Letters Patent, is:—

1. An apparatus of the character described comprising a platform adapted to hold the articles to be fed, guides on the platform, 20 clamping members adapted to engage the side edges of, and frictionally hold between them, the articles to be fed, in combination with means for feeding the articles *seriatim*.

2. An apparatus of the character described 25 comprising a platform adapted to hold the articles to be fed, guides for the articles, spring-pressed means to engage and press against the side edges of the articles, said means comprising an inclined member disposed to exert its maximum pressure on the upper articles, and means for feeding the articles *seriatim*.

3. An apparatus of the character described comprising a platform adapted to hold the 35 articles to be fed, adjustable guides for the articles on the platform, hinged clamping rods projecting below the platform, spring means adapted to press said rods against the sides of the articles to be fed, and means to feed said articles *seriatim*, substantially as described.

4. In an apparatus of the character described, a platform adapted to hold the articles to be fed, adjustable guides mounted 45 on the platform, clamping rods projecting down through the platform, swinging arms which carry said clamping rods, a tension spring adapted to press said rods against the sides of the articles to be fed, and means for feeding said articles *seriatim*.

5. In an apparatus of the character described, a platform adapted to hold the articles to be fed, guides for the articles, means to frictionally engage and press 55 against the side edges of the articles, means to feed the articles *seriatim*, comprising a handle, a reciprocable member movable thereby, and a pusher depending from said member and adapted to frictionally engage the articles *seriatim*, substantially as described.

6. In an apparatus of the character described, a platform adapted to hold the articles to be fed, guides for the articles, means 65 to frictionally engage the side edges of the

articles, means to feed the articles *seriatim*, comprising a hand lever, a reciprocable member movable thereby, and a spring-pressed pusher depending from said member and adapted to frictionally engage the articles *seriatim*, substantially as described. 70

7. In an apparatus of the character described, a platform having guides for the articles to be fed, a hand lever, a reciprocable member movable with the lever, parallel arms journaled to said member, and a pusher journaled to the ends of said arms and adapted to frictionally engage the articles *seriatim*. 75

8. An apparatus of the character described comprising a platform adapted to hold the articles to be fed, guides for the articles, spring-pressed means to engage and press against the side edges of the articles, said means comprising a spring-pressed swinging friction member which is bodily movable 80 toward the stack of articles and inclined, to engage the upper in advance of the lower articles, and means for feeding the articles *seriatim*. 90

9. In an apparatus of the character described, a platform adapted to support a stack of the articles to be delivered, guide means for the articles, horizontally movable swinging arms disposed below the articles, 95 clamp members carried by said arms and adapted to frictionally engage the side edges of the articles, spring means to press said members together, and means to feed the articles *seriatim*. 100

10. In an apparatus of the character described, a platform adapted to support a stack of the articles to be delivered, guide means for the articles, horizontally movable swinging arms disposed below the articles, 105 clamp members carried by said arms and adapted to frictionally engage the side edges of the articles, an adjusting screw in threaded engagement with one arm, a lazy-tong connection between the arms, spring means 110 acting on said screw to move said arms together, means to limit the spring-pressed movement of the screw, and means to feed the articles *seriatim*.

11. In an apparatus of the character described, a platform, horizontally movable arms concentrically pivoted to said platform, lazy-tong connections between said arms, upright guide pins carried by the arms and adapted to engage stacked articles 120 on the platform, and means to feed said articles *seriatim*.

12. In an apparatus of the character described, a platform adapted to hold the articles to be fed, a pair of swinging arms 125 concentrically pivoted below the platform which has arcuate slots above the ends of said arms, a pair of pivotally connected links connecting adjacent ends of said arms, a slide and guide means for the pivoted ends 130

of, said links, an adjusting screw rotatably mounted in the platform, a swiveled block connected to one arm and in threaded engagement with the screw, guide members carried by the arm and projecting above the platform through said slots, and a spring and stop means acting on the screw to maintain tension on said arms throughout their adjustment.

10 13. In an apparatus of the character described, a base comprising a fixed platform and means to frictionally hold in place thereon a stack of articles to be fed, a feed mechanism for the articles comprising a reciprocable member, an elongated pusher arm pivotally connected to said member and adapted to rest at its free end on the uppermost article and to follow down to the bottom-most article, said arm having at its free end means to engage and move the articles *seriatim*, and a handle means for operating said reciprocable member, substantially as described.

15 14. In an apparatus of the character described, a platform and guides thereon for frictionally holding a stack of articles to be fed, a slotted cover through which the articles are fed, and mechanism for feeding the articles comprising a pair of pivoted overhanging rocker arms, a longitudinally disposed bar connecting said arms, a pusher member hinged to the bar, and a handle for oscillating said arms and reciprocating the pusher, substantially as described.

20 15. In an apparatus of the character described, a cabinet having a fixed platform and guides thereon for holding a stack of articles to be fed, and a discharge slot, a sloping wall leading from the platform to the discharge slot, and mechanism for feeding the articles *seriatim* over said wall to the slot comprising a handle, a reciprocable member movable thereby, a pusher arm hinged to the member and adapted to engage the articles and movable with said member toward said slot, and means on the pusher to engage and advance an article, substantially as described.

25 16. In an apparatus of the character described, a base comprising a fixed platform adapted to hold the stacked articles to be fed, means to guide and frictionally engage the articles, a delivery chute for the articles, a top casing hinged to the platform and movable to expose the stacked articles, and mechanism for feeding the articles *seriatim* which is carried by the movable top casing

and comprises a hand-operated reciprocable member, and a pusher driven by said member and adapted to engage and eject the uppermost article.

30 17. In an apparatus of the character described, a base comprising a fixed platform adapted to receive the stacked articles to be fed, and means carried by the base to guide and frictionally hold the stacked articles in place, in combination with a cover hinged to the base and movable to expose the articles and guides, and mechanism carried by the hinged cover for feeding the articles *seriatim*.

35 18. In an apparatus of the character described, a base, means thereon to guide and frictionally hold a stack of articles to be fed, a top hinged to the rear end of the base and having an inclined face at its forward end, there being a slot above said inclined face, and feed mechanism carried by the top and comprising a handle, a reciprocable member operable by the handle, and a pusher hinged to said member, means to hold the free end of said pusher against the articles to be fed, and means on said end to engage and feed the articles, substantially as described.

40 19. In an apparatus of the character described, means to guide and frictionally hold a stack of articles to be fed, and means to feed said articles *seriatim* comprising a reciprocable member, a member carrying a friction pad, and parallel bars disposed in a vertical plane and each pivotally connected at one end to said friction pad member and at the other end to the reciprocable member, substantially as described.

45 20. In an apparatus of the character described, a support for a stack of articles to be fed, means to frictionally hold the articles in stacked position, and means to feed the articles *seriatim*, comprising a reciprocable member, an elongated jointed arm pivotally connected thereto, a rubber pad on the free end of said arm, and a spring at the joint acting to exert a downward pressure on said rubber pad, substantially as described.

50 In testimony whereof we affix our signatures.
